UNITED STATES PATENT OFFICE.

ADOLPHUS G. CANADA, OF MEMPHIS, TENNESSEE.

NON-REFILLABLE BOTTLE.

SPECIFICATION forming part of Letters Patent No. 573,566, dated December 22, 1896.

Application filed February 18, 1896. Serial No. 579,765. (No model.)

To all whom it may concern:

Be it known that I, ADOLPHUS G. CANADA, a citizen of the United States, residing at Memphis, in the county of Shelby and State 5 of Tennessee, have invented certain new and useful Improvements in Non-Fillable Bottles; and I do hereby declare the following to be a full, clear, and exact description of the invention, such as will enable others skilled in 10 the art to which it appertains to make and use the same.

My invention relates to improvements in non-fillable bottles; and it consists in certain novel features hereinafter described and 15 claimed.

It has lately become a more or less common practice for dishonest dealers after a bottle containing a high grade of liquor has become empty to refill this bottle with liquor of an 20 inferior quality without changing the trademark or other means of identification of the original high-grade liquor. It is to prevent this fraud that the herein-described device was invented.

Reference is had to the accompanying drawings, in which the same parts are indicated by the same letters throughout the several views.

Figure 1 represents a central vertical section through the top of the bottle and the 30 auxiliary cork or valve-seat and shows the valve in the position adapted to prevent the refilling of the bottle. Fig. 2 represents a similar section to that shown in Fig. 1, but with the bottle inverted and in the position 35 to pour out liquor. Fig. 3 represents a perspective view of the auxiliary cork or the valve-seat placed in the bottom of the neck of the bottle. Fig. 4 is a perspective view of the valve shown in Figs. 1 and 2, and Fig. 5 40 represents a modified form of the valve wherein only two holding-wings are shown.

A represents the top of the bottle, which bottle may be of any desired or preferred shape, and it may be made of any desired or preferred 45 material, such as glass, pottery, or any other suitable material. This bottle is provided with a neck B, generally similar to those of the ordinary construction, except that the base of the neck tapers internally, as shown 50 at b.

C represents a valve-seat, which should be made of cork, rubber, or other elastic material

which can be pressed firmly down on the taper portion b of the neck and will be held in place by friction. This valve-seat C is 55 provided with a central opening c, enlarged at its open end, as at c', to fit the ball D. Cork or other material not likely to affect the taste of the fluid contained in the bottle should preferably be used. The valve consists of three parts, a ball D, a valve-stem D', and a holding-head D², the whole being made of glass, metal, or other material not likely to affect the taste of the liquid contained in the bottle. The valve-stem D' should preferably 60 be made to fit so as to allow the ready passage of the fluid, but it may be made of any desired shape.

The head D² is provided with a plurality of curved ribs d, having holding-shoulders d', 70 which ribs terminate at their lower ends in a point or tip d⁰, thus producing the effect of one or more arrow-heads attached to the stem D'.

To assemble the parts, the head D² is 75 shoved through the hole c, and the elastic material of which the valve-seat C is made will allow the head to pass and will contract after the head has passed and will prevent the valve from dropping through the said 80 valve-seat when the bottle is inverted. After the valve-seat has been put in position on the valve-stem, the bottle being filled with the liquid intended to be contained therein, the valve-seat and valve are forced down- 85 ward to the position shown in Fig. 1, and then the upper or ordinary cork is put in and the bottle is sealed in the ordinary way.

From an inspection of Figs. 1 and 2 it will be evident that while liquid may be 90 poured out of the bottle liquid cannot be poured into the same without tampering with or removing the valve and the valve-seat. The various advantages of the herein-described construction would readily suggest themselves to any practical mind.

While I have shown the holding-head D² as projecting down into the body of the bottle, the tapering portion b of the neck should preferably be so long as to hold the 100 valve-seat C well up in the middle of the neck, and the lower end of the tapering portion b should be small enough to prevent the passage therethrough of the head D², thus

any possibility of forcing the entire device through the neck into the bottle will be obviated.

It will be obvious that various modifications of the herein-described device might be made and could be used without departing from the spirit of my invention.

Having thus described my invention, what I claim, and desire to secure by Letters Patent of the United States, is—

In a non-fillable bottle, the combination with a neck to said bottle, and a valve-seat rigidly held within said neck and perforated as shown with an enlarged chamber at the upper end of said perforation, and a valve

having a ball adapted to fit snugly in said enlarged chamber, a rigid stem projecting through said perforation, and flat arrow-headed ribs at right angles to each other at the end of said stem adapted to permit a limited play of said valve-stem in said valve-seat, and to lock said stem in said seat, substantially as described.

In testimony whereof I affix my signature in presence of two witnesses.

ADOLPHUS G. CANADA.
